tion October 3, 1936, Serial No. 103,911

8 Claims. (Cl. 260—335)

This application for patent is a division of an application filed by me July 24, 1934, Serial No. 736,631, which is a continuation in part of an application for patent filed by me August 23, 5 1932, Serial No. 630,087.

The present invention relates to a process for producing fluorescent dyes soluble in high boiling aliphatic and aromatic hydrocarbons, particularly lubricating oil, and more particularly to certain 10 dyes of the heterocyclic group containing oxygen in the ring.

In marketing petroleum products such as motor fuels, lubricating oils, etc., it is customary to add certain dyes to these products in order that the 15 purchasers may distinguish between the different brands. In some cases several manufacturers use the same color or different shades of the same color, thereby making it difficult for the purchaser to know whether or not he is getting 20 the products he orders. The producers, who are marketing artificially colored products, are loath to change the colors of their products, and in some cases it is impracticable to do, as certain colors are now widely used to designate certain 25 qualities. Again, it is not desirable to color certain petroleum products, as such coloring would destroy their sales value, the products being graded by their natural colors.

One way to distinguish from one another different brands having the same color is to impart fluorescence of different hues to these products, thereby giving them distinguishing characteristics without substantially altering their colors as viewed by transmitted light. In the 35 case of lubricating oils, imparting a green fluorescence actually enhances the value.

There are many known dyestuffs which will impart fluorescence to alcohol and water and some are known to be soluble in, and impart 40 fluorescence to, lighter petroleum hydrocarbons; but few, if any, are known to be soluble in, and adapted to impart fluorescence to, lubricating oils and which at the same time are known to be stable to light, heat and storage, to be unaffected by metals, to be completely neutral in reaction 45 and not to impart to such oils any qualities which would make them commercially impracticable.

Certain dyestuffs of the heterocyclic group containing oxygen in the ring which are free from 50 nitrogen and sulphur, namely, organic compounds of the coeroxene class (by which term I mean to include coeroxene, its derivatives and substitution products) I have found to be soluble in and effective to impart fluorescence of different 55 shades of green and of varying degrees of intensity to both aliphatic and aromatic hydrocarbons.

So far as I know, none of the dyestuffs of the class mentioned have ever been added to commercial lubricating oil. When added thereto I 60 have found that they are not only soluble there-

in and impart fluorescence thereto, as above stated, but that they possess the other qualities, above enumerated, necessary to render their use for this purpose commercially practicable. I have, for example, found that dimethyl 6,12-5 coeroxenol acetate, when produced by the process hereinafter described, meets all the most exacting requirements.

However, known processes for producing organic compounds of the coeroxene class do not produce these compounds, including the specific compound just above mentioned, in a form entirely acceptable for addition to lubricating oils. The present invention comprises an improved method of producing these compounds, particularly applicable to the production of 6,12-dimethyl coeroxenol acetate and other substituted coeroxenol esters, whereby a high yield of the compound may be produced in its purest state and in a form which renders its use as an addition to lubricating oils highly efficient to produce the desired green fluorescence and ineffective to impart to the oil any undesirable characteristics.

In manufacturing the improved product I proceed as follows, it being understood that those skilled in the art may deviate, without the exercise of invention, from the precise details of the prescribed steps, which are preferable rather than mandatory. It will also be understood that the described specific process is intended for the 30 production of 6,12-dimethyl coeroxenol acetate and that obvious modifications of the process are necessary for the production of other organic color compounds of the coeroxene class.

To a molten mass comprising 220 pounds of 35 paracresol (or a meta or para substituted phenol) and 150 pounds of phthalic anhydride are added 90 pounds of concentrated sulfuric acid or other condensing agent such as phosphorous pentoxide, zinc chloride or stannic chloride.

The mix is then heated with agitation to about 160° C. and maintained at that temperature for about five hours. At the conclusion of this heating step the mass is dumped into (say) 300 40 gallons of water to which is added 100 pounds of 45 caustic soda or any other strong base such as caustic potash or lithium hydroxide. This mix is then boiled for about one hour and the insoluble material which it then contains is separated by filtration and dried. This insoluble material is an intermediate product dimethyl 2,7-50 fluoran and amounts to 200 lbs.

100 pounds of the dimethyl 2,7-fluoran (or any di-substituted 2,7- or 3,6-fluoran produced by the procedure above described by or any obvious variation thereof) is added to 700 pounds of fuming sulfuric acid (oleum) at 20°-25° C. and the mix 55 is continuously agitated for about eight hours, after which it is diluted by pouring into 1200 pounds of water to which has been added about 60

an equal weight of ice. The product is a substituted coeroxonol sulfate—specifically, following the precise procedure above described, a red solution of dimethyl 6,12-coeroxonol sulphate.

5. To this product is added 900 pounds of 28% ammonia, 1800 pounds of ice and 1200 pounds of water, whereby the dimethyl 6,12-coeroxonol base is precipitated. It is of a light grey color. When dried the yield of the base is 95 pounds.
10. After the dimethyl 6,12-coeroxonol base is obtained the heterocyclic compound dimethyl coeroxene may be obtained by reducing the base. This heterocyclic compound, its substitution products and derivatives, as well as its isomers and 15 homologues, produce a green fluorescence when dissolved in aliphatic or aromatic hydrocarbons. For instance, dimethyl 6,12-coeroxonol, its isomers and homologues may be used as well as the acetates, benzoates, phthalates or any organic 20 acid ester of dimethyl 6,12-coeroxonol and its isomers or homologues. Dimethyl 6,12-coeroxonol is not as stable to heat and light as are dimethyl 6,12-coeroxene and the derivatives and 25 substitution products of dimethyl 6,12-coeroxonol so that its use is not recommended when any of the other products herein mentioned are available.

After the coeroxonol base is obtained it is within the knowledge of those skilled in the art to obtain the above mentioned derivatives and substitution products and also others not mentioned which will impart a fluorescence to aliphatic and aromatic hydrocarbons. However, I believe it to be impossible, by the employment of any 30 known process, to secure a commercially economical yield or to secure a product of satisfactory purity, strength, color, or stability to heat or in storage. The following procedure for obtaining the dimethyl 6,12-coeroxonol acetate mentioned 35 has been found to overcome all the objections inherent in known processes.

After the coeroxonol base—in the specific example the dimethyl 6,12-coeroxonol base—is obtained, 100 pounds of the same are mixed with 45 400 pounds of water, 40 pounds of caustic soda or other strong base and 280 pounds of pyridine, or equivalents thereof, e. g., methyl pyridines (picolines), dimethyl pyridenes (lutidines) or other organic solvents soluble in water that do 50 not react with acetic anhydride, such as acetone and dioxan. The mixture is heated to 90° C. and agitated.

Thereafter is added 30 pounds of zinc dust or iron powder. The entire mixture is then agitated 55 for about two hours at 90° C. and cooled to 30° C. after which there is added slowly a suitable acid esterifying agent, such as acetic anhydride, propionic anhydride, butyric anhydride or benzoyl chloride. The mixture is maintained for about 60 two hours at 30° C. and is added to 400 gallons of water, filtered and the product washed and dried. Assuming the addition of the preferred acid esterifying agent—acetic anhydride—the yield is 70–100 pounds of dimethyl 6,12 coeroxonol acetate.

The pyridine or equivalent bases play a dual role, one that of acting as a solvent for the coeroxonol base to facilitate reduction and the other that of a carrier or catalyst for the esterifying agent (acetic anhydride or equivalent). This dual role of pyridine plays an extremely important part in the process.

What I claim and desire to protect by Letters Patent is:

75. 1. The process of producing a substituted co-

eroxonol ester of high purity and yield and suitable for addition to lubricating oil to impart fluorescence thereto which comprises reducing a substituted coeroxonol in an alkaline medium containing an organic solvent soluble in water and that does not react with the subsequently added esterifying agent and then esterifying.

2. The process of producing dimethyl 6,12-coeroxonol acetate of high purity and yield which comprises reducing dimethyl 6,12-coeroxonol in an alkaline medium containing an organic solvent soluble in water and that does not react with acetic anhydride and then esterifying by addition of acetic anhydride.

3. The process of producing dimethyl 6,12-coeroxonol acetate of high purity and yield which comprises treating dimethyl 6,12-coeroxonol with pyridine, caustic alkali and zinc dust and esterifying by the addition of acetic anhydride.

4. The process of producing a substituted coeroxonol ester of high purity and yield which comprises treating a di-substituted fluoran with sulphuric acid and thereby producing a substituted coeroxonol sulphate, precipitating the substituted coeroxonol base, reducing the coeroxonol base in an alkaline medium containing an organic solvent soluble in water and that does not react with the subsequently added esterifying agent, and then esterifying to produce the substituted coeroxonol ester.

30. 5. The process of producing a substituted coeroxonol ester of high purity and yield which comprises treating a di-substituted fluoran with sulphuric acid and thereby producing a substituted coeroxonol sulphate, precipitating the substituted coeroxonol base, reducing the coeroxonol base in an alkaline medium containing pyridine and esterifying by the addition of acetic anhydride.

6. The process of producing dimethyl 6,12-coeroxonol acetate of high purity and yield which comprises treating dimethyl 2,7-fluoran with sulfuric acid and thereby producing dimethyl 6,12-coeroxonol sulphate, precipitating the dimethyl 6,12-coeroxonol base, reducing said base in admixture with water, caustic alkali and pyridine, and esterifying by the addition of acetic anhydride.

40. 7. The process of producing dimethyl 6,12-coeroxonol acetate of high purity and yield which 50 comprises melting together paracresol and phthalic anhydride, adding sulphuric acid, treating the mix with caustic alkali to thereby produce as an intermediate product dimethyl 2,7-fluoran, treating said intermediate product with sulfuric acid and thereby producing dimethyl 6,12-coeroxonol sulphate, precipitating the dimethyl 6,12-coeroxonol base, reducing said base in admixture with water, caustic alkali and pyridine, and esterifying by the addition of acetic anhydride.

8. The process of producing dimethyl 6,12-coeroxonol acetate of high purity and yield which 55 comprises treating approximately 220 parts of paracresol and 150 parts of phthalic anhydride with a condensing agent, and treating the resulting mixture with caustic alkali to thereby produce dimethyl 2,7-fluoran, treating said intermediate product with sulphuric acid to produce dimethyl 6,12-coeroxonol sulphate, precipitating the dimethyl 6,12-coeroxonol base, reducing said base in admixture with water, caustic alkali and pyridine, and esterifying by the addition of acetic anhydride.
